BOTTLE CARRIER

Joseph J. Druhot, Fort Wayne, Ind.

Application November 3, 1944, Serial No. 561,649

2 Claims. (Cl. 294—87)

1

This invention relates to improvements in bottle carriers adapted for use by customers in carrying away bottled goods in small lots and subsequently returning the empty containers for exchange upon making a new purchase.

Ordinarily, carriers for the same purpose are made of flimsy material and are short-lived, necessitating frequent replacements, and generally are so constructed as to require handling of the bottles separately in filling the carrier as well as their removal therefrom.

One object of the invention is to provide a durable carrier that may be used many times without appreciable deterioration.

Another object of the invention is to construct 15 a carrier by which a group of bottles is grasped, automatically secured in the carrier and removed from a case in which they were uniformly arranged, and subsequently transported and deposited into an empty case in similar arrangement without handling the bottles separately.

And a further object of the invention is to provide a bottle securing means for the carrier that operates automatically and holds a group of bottles in orderly arrangement and which readily releases the bottles from the carrier upon manipulation, as with the thumb and finger of one hand by the operator.

And a still further object of the invention is to construct a bottle carrier with but few parts so arranged and assembled that the movable parts are held secured together and in connection with the frame of the carrier without resort to auxiliary fasteners.

Other objects and advantages of the invention appear in the following description.

An illustrative embodiment of the invention is shown in the accompanying drawing, in which:

Fig. 1 is a side elevational view of a structure in which the invention is incorporated, a portion being in section;

Fig. 2 is a top plan view of the structure shown in Fig. 1, a portion being cut away on the line 2—2 thereof; and

Fig. 3 is a vertical cross sectional view of Fig. 2 on the line 3—3 thereof.

The illustrative embodiment of the invention consists of a hanger frame shaped to include a base-bar 4 provided with an upwardly extending handle 5 and a series of similar oblong bottle-neck encircling members 6, 7 and 8. The handle and said members are preferably integral with the base-bar and formed of a single casting. The bottle-neck encircling members are open through their tops and bottoms and are spaced suitably

2

apart from each other, and each is adapted to receive the neck of a pair of bottles, the arrangement being such that each bottle positioned in the hanger frame will be held equally spaced apart from the adjacent bottles.

An open recess 9 is made in the upper portions of the encircling members that extends longitudinally parallel with the base-bar 4 and equilaterally therefrom a suitable distance, for reception of a pair of lock-bars 10, one on each side of the handle. Each bar has a pair of lugs 11 that project laterally from its inner edge and extend loosely into corresponding openings 12, made in the handle at its junctures with the base-bar, so as to permit upward hinged movement of the lock-bars relative to the hanger frame. The outer marginal side portions of each bar has made therein a series of adjacent indentations 13 that are curved oppositely with respect to the adjacent curved end walls of the corresponding encircling members so there are formed a series of bottle-neck receiving openings 15 through which the upper ends of a corresponding series of bottle-necks project when in place. Each bar 20 is shaped to have along its outer lateral edge a pair of finger-holds 16, preferably located respectively above the spaces between adjacent encircling members, to afford convenience in tilting the bars upwardly by applying manual pressure 25 against the bottom face of one or the other of the finger-holds.

The lock-bars 10 are normally held within the recess 9 by means of a spring fixture 17 preferably formed of a single piece of wire shaped to have 30 two divergent contracting coils 18. The mid-portion of the fixture extends astride the lower edge of the base-bar within the middle encircling member 7, and its terminal ends are hooked in connection with the respective lock-bars, thus 35 serving to hold the hanger frame and lock-bar assemblage together and permit opening movement of the lock-bars selectively.

In using the invention the carrier, while held pendently by its handle, is lowered over an assemblage group of bottles, whereupon the top of the bottles protrude into the encircling members and contact with the lock-bars causing them to move 40 hingedly upward as the hanger frame is lowered thus permitting the tops of the bottles to protrude beyond the tops of the members. Subsequently, upon elevating the carrier, the necks of the bottles become clamped between the adjacent lock-bars and the opposing end walls of the encircling members and are then bodily lifted together with the carrier and transported.

The bottles are released from the carrier and left in the original assembled order by first resting the group of bottles on the place of deposit, then swinging the lock-bars upwardly into disengaging position, after which the carrier is raised free from engagement with the bottles.

In Fig. 3 is illustrated a bottle 19 of the usual type of beverage container having an external annular shoulder 20 on its upper end portion which when in locked position overhangs the tops of the corresponding encircling member and the adjacent lock-bar. In this manner removal of the bottle from the hanger frame is prevented until the lock-bar with which it is engaged is swung upward to permit its release.

An advantage of the invention is that the carrier is easily operated with the use of but one hand, or, two carriers may be operated at the same time using both hands independently of each other. This is afforded by the automatic operation of the lock-bars in loading the carrier, and the location of the finger-holds on the lock-bars in proximity to the handle within convenient reach of the thumb and finger of the hand by which the carrier is held while unloading.

Variations from the particular construction above disclosed may be resorted to by the exercise of skill in the art, without departure from the scope of the invention, and the following claims are intended to be inclusive of such variations.

What I claim is:

1. In a bottle carrier, a hanger frame shaped to include a base-bar, a series of similar oblong bottle-neck encircling members supported by the base-bar and handle in connection with the frame, said frame having in its top a recess extending longitudinally parallel with the base-bar and equilaterally therefrom, lock-bars dis-

posed in said recess having lugs projecting from their opposing edges into openings in the hanger frame structure, adapted for hinged movement upwardly respecting the frame, the outer edges of said lock-bars having indentations located oppositely with respect to the adjacent end walls of the corresponding encircling members, and having finger-holds by which to manipulate said lock-bars, and a spring fixture having divergent contracting coils disposed astride of the base-bar and connected respectively with said lock-bars, thus to secure the lock-bars in connection with the frame and hold them normally in bottle-neck engaging position.

2. A bottle carrier consisting of a hanger frame having a base-bar provided with an upstanding handle and a series of bottle-neck encircling members transversely disposed in connection with the base-bar, a pair of lock-bars disposed one on each side of the handle, each having lugs projecting laterally from its inner edge loosely into corresponding openings in said frame to secure said lock-bars for upward hinged movement, the outer lateral edges of said lock-bars having indentations for reception of bottle-necks respectively when disposed in said members, each lock-bar having a finger-hold disposed so as to be engageable by the thumb or a finger of the operator's hand while grasping the handle wherefore to operate said lock-bars selectively, and a spring fixture engaged with said base-bar around the lower edge thereof provided with divergent retracting coils connected respectively with said lock-bars to secure the frame and lock-bar assemblage together and to yieldingly hold the lock-bars in bottle-neck engaging position so as to permit selective operation thereof.
